UNITED STATES PATENT OFFICE.

ABNER Y. LEECH, JR., OF WASHINGTON, DISTRICT OF COLUMBIA, ASSIGNOR TO UNITED STATES ORDNANCE COMPANY, OF WASHINGTON, DISTRICT OF COLUMBIA, A CORPORATION OF VIRGINIA.

FIRING MECHANISM FOR GUNS.

No. 925,642.

Specification of Letters Patent.

Patented June 22, 1909.

Application filed December 24, 1907. Serial No. 407,901.

To all whom it may concern:

Be it known that I, ABNER Y. LEECH, Jr., a citizen of the United States, residing at Washington, in the District of Columbia, have invented a new and useful Improvement 5 in Firing Mechanism for Guns, of which the following is a specification.

My invention relates to firing mechanism 10 for guns and comprises improved means for igniting the primer either electrically or by percussion.

In describing the invention in detail reference will be had to the accompanying drawings, which form part of this specification, 15 and in which,

Figure 1 is a vertical section of the breech mechanism of a gun equipped with my invention; the breech block being shown closed and locked and the mechanism ready to be 20 operated electrically or percussively; Fig. 2, a view similar to Fig. 1, the firing pin being retracted and the block still locked; Fig. 3, a view similar to Fig. 1, the breech block being unlocked ready for withdrawal; Fig. 25

4, a view similar to Fig. 1, the firing mechanism being shown in the position assumed by the various parts at the moment of firing percussively; Fig. 5, a horizontal section of the breech mechanism; Fig. 6, a rear elevation 30 of the breech of a gun equipped with my invention and Fig. 7 is a plan view partly broken away showing the operating bar of the breech mechanism.

Referring to the drawings, A represents 35 the breech of a gun containing my invention; having a central bore and powder chamber A¹ and an eccentric breech chamber A², segmentally threaded, as at A³. The breech block B has correspondingly threaded 40 segments B¹; in the usual way, or other suitable engagement between the gun and, block may be had.

C is a breech block carrier, hinged to the gun at Q and having a forwardly projecting 45 hub C¹ C² eccentric to the bore A¹, but concentric with the breech chamber. Thus hub fits a corresponding cavity in the breech block and the latter revolves thereon in locking and unlocking.

50 An operating-lever L is engaged by the operating-shaft Q and operates the breech mechanism. For this purpose a transversely sliding bar F is mounted in the carrier adjacent to the operating-lever L and has a

slot F¹ engaged by a stud L¹ on the operating-lever, whereby the swinging of the lever causes a sliding of the bar. A slot F² in the front face of a lug F³ on the bar engages a stud B⁶ in the rear face of the breech block, whereby sliding of the bar causes rotation 55 of the breech block. A cam surface F⁴ on the bar F engages a lug D⁵ on the firing pin projection in such a manner that the first movement of the bar F retracts the firing pin D, after which the block is rotated 60 to open the breech: in closing the breech the block is rotated to its locked position by the bar F; the cam surface F⁴ permitting the pin D to move forward and make contact with the primer. The width of the slot 70 F² is in excess of the diameter of the lug B⁶ whereby the first movement of the bar F retracts the pin D through the medium of the cam F⁴ and lug D⁵, but will not rotate the breech block until the bar F has moved 75 a sufficient distance to bring the outer edge of the slot F² into engagement with the lug B⁶.

The carrier hub is pierced by the longitudinal chamber C³ C⁴. In this chamber is 80 inserted and secured the firing case K, in which the firing mechanism, both electric and percussion, is secured and carried. The case K is secured in the carrier by the lug K¹ and engages the breech block by the finger K². It is removed from the carrier by a partial revolution and withdrawal, the projections K¹ K² having corresponding run-outs. 85

The breech block B has a perforation B³ 90 in its front face, expanding rearwardly into a recess B⁴, to receive the firing pin D. The recess and perforation B³ are eccentric to the axis of the breech block and so disposed as to be in axial alinement with the firing 95 pin D (and with the bore of the gun) only when the block B is in its locked position: they will swing out of such alinement upon rotation of the block to unlock, coming finally to the relation with the firing pin and 100 bore illustrated in Fig. 3. It is therefore impossible for the firing pin to move forward or fire the gun until the breech block is in its completely locked position, since in any other position the face B⁵ would prevent the forward movement of the pin D. 105

Secured and mounted in the firing case K is the firing pin D, which has a contact

point D¹, for both electric and percussion firing, an angular shoulder D⁴ and a rearward projection D². The spring D³ maintains the pin in contact with the primer P when the block is locked. The projection D² extends through the rear of the firing case and has a suitable connection (D⁸ D⁶) for the attachment of the electrical conductor (D⁷).

10 The mechanism for firing the gun percussively in conjunction with the firing pin D is mounted in the firing case K adjacent the projection D² and in the rear of the shoulder D⁴ of pin D. This mechanism consists of a hammer M telescoping with a sleeve M¹ and a spring E inclosed between said hammer and sleeve. A pin M⁴ in the closed end of sleeve M¹ enters a groove M⁵ in the hammer M locking together spring, hammer and sleeve and preventing rotation of the sleeve and hammer with relation to each other. A lever arm H pierces a slot M⁶ in hammer M and engages the outer end M⁸ of sleeve M¹. The arm H is adapted to be rotated through the medium of a shaft G which has one end detachably keyed to the arm and provided at its other end with a trigger J to which a lanyard may be suitably secured.

15 N is a sear adapted to engage the hammer M when in its retracted position (see Fig. 1). The sear N is shown as a sleeve having one end closed and provided with a catch N¹ adapted to engage a notch M⁷ of hammer M. A spring N² mounted within the sear N normally tends to hold the catch N¹ in engagement with the notch M⁷. The sear N is released from engagement with hammer M by the rotation of the arm H which is provided near its fulcrum point with a toe 20 H¹ which when the arm H has been sufficiently rotated engages an oppositely disposed toe N⁸ of the sear and causes a compression of the spring N² and the withdrawal of the catch N¹ from the notch M⁷.

25 The operation of firing the gun percussively is as follows: The parts being in their normal positions (Fig. 1) the trigger J is pulled to the rear by a lanyard rotating the shaft G and arm H. The arm H moves the sleeve M¹ forward compressing the spring E. At this moment the sear N begins to hold the hammer M from forward movement and continues to do so until the toe H¹ of the arm H engages the toe N⁸ of the sear and 30 causes the withdrawal of the catch N¹ from the notch M⁷. Upon such withdrawal the hammer M flies forward under the influence of the compressed spring and strikes the shoulder D⁴ of the firing pin D causing the pin D to strike and explode the primer. When the pull of the lanyard is released, the spring through the sleeve M¹ forces the arm H to the rear when it encounters the hammer M at the end of slot M⁶. Since the 35 spring exerts equal pressure in both direc-

tions—rearwardly against the arm H through the medium of the sleeve M¹, at the point H⁴ and forwardly against the hammer—the rearward pressure of the spring against the extremities H⁴ of the arm is equal to the forward pressure of the hammer against the middle portion of said arm at H⁵ and they tend to move the arm in opposite directions; but as the point of application of the force at H⁴ is at a greater distance from the fulcrum of the arm H than that of the force at H⁵ its leverage predominates and the arm, and with it the firing-hammer, is returned to its normal position (shown in Fig. 1) and the cycle of operations is complete.

40 When the term "combined electric and percussion firing mechanism" occurs in the specification and claims it is intended to indicate that the operator may utilize either the electric or percussive element to fire the gun.

I claim:

1. The combination with a breech-loading gun, of a breech block revoluble eccentrically to the bore and a combined electric and percussion firing mechanism.

2. The combination with a breech-loading gun, of a breech block revoluble eccentrically to the bore and opened to the rear; and a combined electric and percussion firing mechanism.

3. The combination with a breech-loading gun in which the breech block is arranged eccentric to the bore and secured in operative relation thereto by an interrupted thread; of a combined electric-percussion firing mechanism.

4. The combination with the rotatable breech block of a gun, of a firing pin having a contact point normally projecting beyond the face of the breech block, means for connecting it with an electric conductor, means for retracting the firing pin before the initial rotation of the block in unlocking and for gradually moving the pin forward as the block is locked.

5. The combination with a breech-loading gun; of a rotatable breech block, a firing pin adapted to fire the gun electrically, and a normally retracted firing hammer adapted to strike the pin and fire the gun percussively.

6. The combination with a breech-loading gun; of a breech block revoluble eccentrically to the bore, a firing pin having a contact point normally projecting beyond the face of the breech block, means for connecting it with an electric conductor, means for completely retracting the firing pin before the initial rotation of the block in unlocking and for gradually moving the pin forward to its normal position as the block is locked.

7. The combination with a breech-loading gun; of a rotatable breech block eccentric to the bore, a firing pin adapted to fire the gun

electrically, and a normally retracted firing hammer adapted to strike the pin and fire the gun percussively.

8. The combination with a breech-loading

5 gun; of a breech block revoluble eccentrically to the axis of the bore and a combined electric-percussion firing pin constantly supported in the axis of the bore.

9. The combination with a breech-loading

10 gun; of a breech block revoluble eccentrically to the axis of the bore, a carrier, and a combined electric-percussion firing pin constantly supported in the axis of the bore by the carrier.

15 10. The combination with a breech-loading gun; of a rotatable breech block and a combined electric-percussion firing pin having a fixed position with relation to the gun, said breech block having an aperture alined with

20 the firing pin when the block is locked and out of alinement with said pin when the block is partially or wholly unlocked.

11. The combination with a breech-loading gun; of a rotatable breech block, a combined 25 electric-percussion firing pin and a barrier interposed between the pin point and the primer of the charge in the partially or wholly unlocked position of said block.

12. The combination with a breech-loading 30 gun; of a rotatable breech block, a combined electric-percussion firing pin, and a shiftable barrier adapted to be interposed between the firing pin point and the primer of the charge in the partially or wholly unlocked position

35 of said block.

13. The combination with a breech-loading gun; of rotatable breech block eccentric to the axis of the bore, a combined electric and 40 percussion firing mechanism and means constituting a barrier to said mechanism in the partially or wholly unlocked position of said block.

14. The combination with a breech-loading gun; of a rotatable breech block eccentric to the axis of the bore, a firing pin 45 adapted to fire the gun electrically, and a firing hammer adapted to strike the pin and fire the gun percussively.

15. The combination with a breech-loading 50 gun; of a rotatable breech block, a firing pin adapted to fire the gun electrically, and a normally retracted firing hammer mounted independently of the firing pin and adapted to strike same to fire the gun percussively.

55 16. The combination with a breech-loading gun; of a rotatable breech block, a firing pin adapted to fire the gun electrically, and a hammer adapted to strike the pin and fire the gun percussively, and means for retract-

ing the pin from and replacing it in its normal position without effect on the actuating mechanism of the hammer.

17. The combination with a breech-loading gun; of a rotatable breech block eccentric to the axis of the bore, a firing head 65 having a stem secured thereto out of alinement with said head through the medium of a shoulder for firing the gun electrically, and a firing hammer in alinement with said head adapted to strike same and fire the gun 70 percussively.

18. The combination with a breech-loading gun; of a rotatable breech block eccentric to the axis of the bore, a firing pin adapted to fire the gun electrically and a 75 continuous pull firing hammer adapted to strike the pin and fire the gun percussively.

19. The combination with a breech-loading gun; of a rotatable breech block eccentric to the axis of the bore, a carrier, a firing 80 case mounted in said carrier, a combination electric-percussion firing device secured in the firing case, said firing case interlocking with the block and carrier.

20. The combination with a breech-loading gun; of a rotatable breech block, a firing pin adapted to fire the gun electrically, a firing hammer adapted to strike the pin and fire the gun percussively and means for retracting said pin from and replacing it in 90 its normal position independent of the hammer.

21. The combination with a breech-loading gun; of a rotatable breech block eccentric to the axis of the bore, a combined electric-percussion firing pin and a transversely 95 movable member adapted to retract said pin before the initial rotation of the block to unlock.

22. In breech-loading gun, a member rotatable eccentrically to the axis of the bore of the gun, a firing pin projecting through said member and adapted to fire the gun electrically, and a firing hammer adapted to strike the pin and fire the gun percussively. 105

23. In a breech-loading gun, a member rotatable eccentrically to the axis of the bore of the gun, a firing pin adapted to fire the gun electrically, and a normally retracted firing hammer adapted to strike the pin and 110 fire the gun percussively.

In testimony whereof I have signed my name to this specification in the presence of two subscribing witnesses.
